UNITED STATES PATENT OFFICE.

EDWARD L. GOSSE, OF CHANUTE, KANSAS, ASSIGNOR OF ONE-HALF TO
LOUIS A. LAUGHLIN, OF KANSAS CITY, MISSOURI.

OIL-WELL PUMPING APPARATUS.

No. 801,981.

Specification of Letters Patent.

Patented Oct. 17, 1905.

Application filed October 4, 1904. Serial No. 227,121.

To all whom it may concern:

Be it known that I, EDWARD L. GOSSE, a citizen of the United States, residing at Chanute, in the county of Neosho and State of Kansas, have invented certain new and useful Improvements in Oil-Well Pumping Apparatus, of which the following is a specification.

This invention relates to oil-well pumping apparatus, and more especially to that class utilizing compressed air for effecting the discharge of the oil from the well, and has for its object to produce apparatus for pumping practically only a high-grade oil—that is, oil comparatively or wholly free from sediment, sand, and particles of rock.

A further object is to produce apparatus whereby sand, small particles of rock, and other foreign substances may be "shot" from the well when the capacity of the latter has fallen in an undesirable degree because of the excessive accumulations in the well of such foreign substances.

A still further object is to produce oil-well pumping apparatus comprising a chamber to receive the oil and provided at its lower end with an opening, and a movable oil-discharge pipe to receive the oil from said chamber, having a valve at its lower end to normally close said oil discharge or exit opening, together with means whereby any accumulation of sand and other foreign particles may be forced out of said chamber and shot from the well.

Another object is to produce an oil-pumping apparatus which is of simple, strong, and durable construction, which can be easily secured in or removed from position, and which as compared with the results of its use is inexpensive.

With these objects in view the invention consists in certain novel and peculiar features of construction and organization, as herein-after described and claimed, and in order that it may be fully understood reference is to be had to the accompanying drawings, in which—

Figure 1 represents a side elevation of an oil-well pumping apparatus embodying my invention, the same being shown in operative relation to a well. Fig. 2 is an enlarged vertical section of the lower part of the same. Fig. 3 is a vertical section of the upper part of the same.

In producing an oil-well a boring 1 is made

in the usual manner, the same extending down into the oil-bearing sand 2 and almost invariably through a stratum of rock, as at 3, encountered before such sand is reached. The well is then shot by means of a charge of nitroglycerin lowered a suitable distance into such sand and exploded, the result being that a large volume of sand mixed with pieces of rock and other foreign particles is discharged upward through the boring, and a well 4 is produced in the sand, which well is soon filled with oil, as at 5.

A casing in the form of a pipe 6, or rather a series of pipes connected together, is fitted with a substantially oil-tight joint in the boring and usually extends down through the same into the stratum of rock just above the oil-bearing sand, as the boring need not be equipped with the casing in the rock 3, it being understood, of course, that if earth is encountered between the stratum and oil-bearing sand the casing must also extend through such earth. Practically all wells are equipped with the casing described.

Extending down through the casing probably to about the plane of the upper surface of the oil-bearing sand and of materially less diameter than said casing is a pipe 7, the upper end of said pipe being attached, by preference, to an L-coupling 8, having an opening 9 in line with its vertical center and having its horizontal arm coupled to a pipe 10, leading from a suitable air-pressure apparatus. (Not shown because of common and well-known construction.) The lower end of said pipe 7 is secured rigidly in a nut 11, forming an enlargement for said pipe, and depending rigidly from said nut, and of preferably twice the diameter of pipe 7 is a casing 12, said casing being of length to extend nearly to the bottom of the well, by preference, and secured to the end of said casing is a cap 13, provided with a central valve-seat opening 14. The casing is provided at a suitable distance above its lower end with one or more openings 15 for the admission of oil, and controlling said openings are pivoted or equivalent flap-valves 16, said valves being adapted to open under the pressure of the oil from the well and to close under a heavier pressure applied within the casing.

17 designates a pipe of materially smaller

diameter than and extending through pipe 7, the opening 9 of coupling 8, and the packing box 18 thereof, said pipe 17 terminating contiguous to the bottom of the casing. Sur-
 5 mounting pipe 17 is a T-coupling 19, controlled by a three-way valve 20, and connected to the opposite end of the coupling from pipe 17 is a pipe 21 to conduct the oil to a suitable storage-tank or other receptacle, (not
 10 shown,) a pipe 22 connecting the stem of the coupling to the air-pressure apparatus hereinbefore referred to. Near its lower end pipe 17 is provided with an intake-opening 23 and below the same carries rigidly a valve 24, normally seated in and closing opening 14, the valve being provided with an upwardly-tapering portion 25 and with a depending prong or point 26 for purposes which hereinafter appear.
 15
 20 With an apparatus as thus constructed and arranged it will be apparent that the oil from the well will seek its level in the casing by entrance through valve-controlled openings 15—that is, of course, when air is not being forced down through pipe 7 or through said pipe and pipe 17. To effect the discharge of oil into the tank or other receptacle, valve 20 is disposed as shown in full lines, Fig. 3, and the air is forced down through pipe 7 into
 25 the casing and upon the body of oil therein. This pressure of the air upon the oil forces the same downward and closes valves 16, so that the oil from the casing and that which stands at the same level in pipe 17 shall be forced up through said pipe, valve 20, and pipe 21 to the tank or other receptacle, this action continuing until practically the entire volume of oil has been forced out of the casing. As the air-pressure to effect the pur-
 30 pose described will vary according to the depth of the well—that is, will have to increase as the depth of the wells increase—it will be apparent that an exceedingly-heavy pressure will be necessary to effect the dis-
 35 charge of oil from very deep wells. I have found, however, by discharging a small proportion of said air into pipe 17 at a suitable distance above the opening 23, and preferably above the level of the oil, that the oil
 40 can be raised and discharged under a pressure of air materially less than is necessary when such division of air does not take place, and to accomplish this result I preferably provide pipe 17 with a small hole or leakage-passage
 45 27. If the hole occurs above the oil-level, the air passing therethrough in pipe 17 tends to create a vacuum, and therefore to remove atmospheric pressure from the path of the oil flowing upward through said pipe. If said
 50 hole occurs below the level of the oil, it will displace a proportionate volume of the oil, and as a result the whole body of oil will be discharged with less pressure than would otherwise be required. In time the well will

fill up with loose sand and other foreign sub-
 65 stances to such an extent that the flow of oil into the casing will be materially checked, and consequently diminish the volume of oil obtained. When this occurs, the person in charge of the apparatus operates valve 20 to close pipe 21 and open communication be-
 70 tween pipes 19 and 22 and then in any suitable manner lifts pipe 17 to raise valve 24 from its seat. The air now passes down through pipe 7 and into casing 12, as before, and passes thence through opening 14 into the well and blows the loose sand and other small foreign particles, together with oil, out of the well and up through the casing externally of pipe 7. This oil, sand, and other foreign par-
 75 ticles may be caught in any suitable manner for the purpose of saving the oil or may go to waste, as the cost of saving and straining said oil may exceed its value. It will be ob-
 80 vious, of course, that this operation will result in forcing any sand or foreign particles out of the casing which may have entered the same through the valve opening or openings 15, and in order to prevent any foreign par-
 85 ticles from being blown up into pipe 17 it is preferable to force the air down through said pipe at the same time that it passes through pipe 7. After the well has been thus cleared of obstructions to the proper flow of oil into the casing the valve 24 is reseated and the po-
 90 sition of valve 20 reversed, so that the appa-
 95 ratus is again ready for pumping oil.

In a well about eight hundred feet deep the one-inch pipe 17 will be so heavy that valve 24 will reliably maintain its seat by 100 gravity, and because of this weight it will be apparent that it is desirable to have the upper part of the valve taper, as at 25, so that any sand which may be in the casing will not be resting directly on the valve and add mate-
 105 rially to the weight to be raised in unseating the same. It will also be apparent by reason of the weight of the pipe that when the valve is lowered it will resume its seat properly, be-
 110 cause any loose sand which might fill up the bottom of the casing will be penetrated and pushed aside easily by the depending point 26, and thus afford no material obstruction to the reseating of the valve.

It has been demonstrated in actual practice 115 by having the valve opening or openings 15 at a material distance above the bottom of the well that practically nothing but high-grade or pure oil is obtained—in fact, practi-
 120 cally all sediment is below the valve-openings, and therefore does not enter the casing. It is to be understood, however, that if the oil is pumped before it has time to settle prop-
 125 erly after the well is shot for the purpose of removing clogging material, as hereinbefore explained, it may contain more or less float-
 ing sediment or foreign matter, and in such case would have to be graded. By waiting a

comparatively short time, however, the sediment will settle in the well to a point below the opening or openings 15, and the oil obtained will not need grading.

5 In setting up the apparatus the casing is first secured upon the end of pipe 7 and then lowered in place and is of course secured in the desired position in any suitable manner. The pipe 17 is then equipped with the valve 10 and is lowered to position, the valve being of such diameter that it will pass through pipe 7.

It is preferred that the internal diameter of casing 12 and pipes 7 and 17 shall respectively be four inches, two inches, and one inch, 15 though I do not limit myself to such relative proportions of the parts nor to the use of a casing separate from pipe 7, as said casing in reality forms a part of said pipe. In fact, said casing need not be of any greater diameter than the pipe, though it is preferred to 20 make it larger.

From the above description it will be apparent that I have produced an oil-well-pumping apparatus possessing the features of advantage enumerated as desirable in the statement of the object of the invention and which obviously may be modified in various particulars without departing from the principle of construction involved.

30 Having thus described the invention, what I claim as new, and desire to secure by Letters Patent, is—

1. An oil-pumping apparatus, comprising a pipe, having an opening at its extreme lower end and one or more valve-controlled openings 35 above the first-named opening, and a pipe extending through the first-named pipe and provided with an opening near its lower end and with a valve normally closing the opening in the lower end of the first-named pipe.

2. An oil-pumping apparatus comprising an air-tubing provided in its lower end with a blow-out opening and above said end with a valve-controlled opening for the admission of 45 oil, and an oil-discharge tube within the air-tubing provided with an oil-passage near its lower end, the lower extremity of the said oil-discharge tube constituting a valve normally closing the blow-out opening in the 50 lower end of the air-tubing.

3. An oil-pumping apparatus, comprising a pipe, having an opening at its lower end, and one or more valve-controlled openings above 55 the first-named opening, and a pipe extending through the first-named pipe and provided with an opening near its lower end and a valve normally closing the first-named opening of the first-named pipe, said valve having a part depending through said first-named opening 60 and below the first-named pipe.

4. An oil-pumping apparatus, comprising a pipe, having an opening at its lower end, and one or more valve-controlled openings above the first-named opening, and a pipe extending

through the first-named pipe and provided 65 with an opening near its lower end and a valve normally closing the first-named opening of the first-named pipe; said last-named valve having an upwardly-tapering portion and a part depending through said first-named opening and below the first-named pipe. 70

5. An oil-pumping apparatus, comprising a pipe, a casing depending rigidly from the lower end of said pipe and provided at its extreme lower end with a blow-out opening and above 75 said end with one or more valve-controlled openings, a pipe extending loosely through the first-named pipe and into said casing and having an opening near its lower end, and a valve secured rigidly to the lower end of the 80 last-named pipe and normally closing said blow-out opening.

6. An oil-pumping apparatus, comprising a pipe having a blow-out opening at its extreme lower end and one or more valve-controlled 85 openings above the blow-out opening, and a pipe extending loosely through the first-named pipe and having a leakage-passage a suitable distance above its lower end, an opening near its lower end and a valve depending from its 90 lower end and normally closing the blow-out opening of the first-named pipe.

7. An oil-pumping apparatus, comprising a pipe, a casing depending rigidly from the lower end of said pipe and provided at its extreme 95 lower end with a blow-out opening and above said end with one or more valve-controlled openings, a pipe extending loosely through the first-named pipe and into said casing and having an opening near its lower end and a 100 leakage-passage a suitable distance above the casing, and a valve secured rigidly to the lower end of the last-named pipe and normally closing the blow-out opening.

8. An oil-pumping apparatus, comprising a 105 pipe having an opening at its lower end and one or more valve-controlled openings above the first-named opening, a pipe extending through the first-named pipe, provided with an opening near its lower end and a valve 110 normally closing the first-named opening of the first-named pipe; said second or inner pipe projecting up through and out of the first-named pipe, a pipe to conduct air under pressure into the first-named pipe externally of 115 the inner pipe, a pipe to conduct air under pressure into the upper portion of the inner pipe, and a valve to cut off the escape of such air from the upper end of said inner pipe.

9. An oil-pumping apparatus, comprising a 120 pipe having an opening at its lower end and one or more valve-controlled openings above the first-named opening, a pipe extending through the first-named pipe provided with an opening near its lower end and a valve 125 normally closing the first-named opening of the first-named pipe; said second or inner pipe projecting up through and out of the first-

named pipe, a pipe to conduct air under pressure into the first-named pipe externally of the inner pipe, a pipe to conduct air under pressure into the upper portion of the inner pipe, and a three-way valve located to open communication between the conducting-pipe and the inner pipe below said valve, or to open up the passage of the inner pipe and close

communication of the same with the conducting-pipe.

In testimony whereof I affix my signature in the presence of two witnesses.

EDWARD L. GOSSE.
